TOY METAL EMBOSSED MACHINE

Willis E. Rexford, Girard, and Raymond Lohr,
Erie, Pa., assignors to Louis Marx & Company,
Inc., New York, N. Y., a corporation of New
York

Application June 25, 1938, Serial No. 215,848

17 Claims. (Cl. 197—6.4)

This invention relates to embossing machines, especially for embossing letters or numbers on a metal tape, and more particularly to such a machine designed for use by children.

The primary object of the present invention is to generally improve embossing machines, and a more particular object resides in the provision of such a machine adapted for manufacture and sale at a reasonable price for use as a toy by children. With this same object in view, the machine is so designed as to be safe in operation, the parts being so arranged as to make it difficult for a child to injure himself when using the machine.

To the accomplishment of the foregoing general and other more particular objects which will hereinafter appear, the invention consists in the embossing machine elements and their relation one to the other, as are hereinafter more particularly described in the specification and sought to be defined in the claims. The specification is accompanied by drawings, in which:

Fig. 1 is a plan view of an embossing machine embodying features of the present invention;
25 Fig. 2 is a side elevation of the same;
Fig. 3 is a front elevation of the same;
Fig. 4 is a section taken in the plane of the line 4—4 of Fig. 1;

Fig. 5 is explanatory of the manner in which 30 the tape is severed by the cutting die;
Fig. 6 is a bottom view of the machine showing the relation of the parts when the operating lever is elevated;

Fig. 7 is a similar view showing the relation of 35 the parts when the operating lever is depressed;

Fig. 8 is a longitudinal section taken in the plane of the line 8—8 in Figs. 1 and 3; and

Fig. 9 is a transverse section through the movable printing wheel, it being taken in the plane 40 of the line 9—9 of Fig. 8.

Referring to the drawings, the machine comprises a base 12 on which is mounted a stationarily journaled printing wheel 14 and a movably journaled printing wheel 16. Wheel 14 may be rotated by means of a knob 18 to select any desired letter or character to be printed. Appropriate gearing is provided within base 12 for simultaneous rotation of wheel 16, thus keeping the wheels in registration. The wheels may be 45 relatively moved to impress the letter on tape 20 by means of an operating handle 22. This is done through the medium of a pusher 24 which bears against the periphery of wheel 16 and moves it toward wheel 14. The handle 22 is 50 stored to its upward position by a suitable re-

storing spring carried within base 12, and during the restoring movement tape 20 is fed forwardly by appropriate feed wheels 26 and 28. A roll of tape is carried in housing 30, and the tape is fed intermittently in step-by-step fashion as 5 the printing wheels are actuated. After the tape has been embossed with a name or other information, the printed length of tape is severed by means of a cutting die generally designated 32 and operated by means of a separate operating 10 handle 34.

Considering the mechanism in greater detail, the printing wheel 14 is preferably cast to finished shape, as by means of die-casting, though it may, of course, be formed in other ways. It is 15 formed integrally with the knob 18, as is best shown in Fig. 8. The upper surface 36 is appropriately colored and has lettered thereon a series of letters and numerals, as is clearly shown in Fig. 1. These correspond to the impressions 20 on the periphery of the wheel. In the present example, the wheel 14 is a female wheel and the various letters and numbers are indented in the surface of the wheel, as is clearly shown in Fig. 3 on the periphery of the wheel. If the wheel 25 is made by die-casting, the letters may be formed as a part of the die-casting operation. The wheel 14 is hollowed on its underside to form the space 40, best shown in Fig. 8, thus providing room for a substantial bearing 42. The wheel is formed 30 integrally with a shaft or journal 44 received in bearing 42. The lower end of shaft 44 is squared at 46 and receives a spur gear 48 which may be stamped out of sheet metal. Gear 48 is secured on squared end 46 by riveting the end of the 35 shaft against the gear. Printing wheel 14 is supported against downward movement by reason of the fact that it rests directly on the upper surface of base 12. It is supported against upward movement because gear 48 bears against 40 the lower end of bearing 42. Bearing 42 is fixedly secured to the base by driving the lower part of the bearing through a mating aperture in the base as far as the collar 50, whereupon the lower end of the bearing may be staked or otherwise 45 upset, as is indicated at 52, in order to lock the bearing in place.

The movable wheel 16 mates with wheel 14, and in the present case the wheel 16 is, therefore, male, that is, it has raised letters on its 50 periphery. No knob is needed or provided for wheel 16. It is also not essential to provide letters on the top surface of the wheel, but in the present case such letters have been provided, as is clearly shown in Fig. 1, thus illustrating at 55

- all times the proper registration of the two wheels. Wheel 16, like wheel 14, is formed integrally with a shaft 54 having a squared lower end 56. Shaft 54 is journaled in a bearing 58. This bearing may be die-cast and is formed integrally with a rectangular plate 60, said plate being received in a rectangular slot 62 in base 12. Referring to Fig. 7, it will be seen that the width of slot 62 equals the width of plate 60, but that slot 62 is longer than plate 60, thus permitting a limited movement of the plate toward or away from the stationary wheel. The plate is guided between bearing plates 64 secured above base 12, as is best shown in Fig. 9, and rivet heads 66 located below base 12. Plates 64 are riveted in place by means of rivets 68, and the heads of these rivets are made so large as to overlap the bottom of slidable plate 60, as is clearly shown in Figs. 7 and 9. The bearing is normally moved away from the stationary printing wheel by resilient means, here exemplified by a spring 70 best shown in Fig. 8, said spring being located between a bracket 72 secured to the base and bearing 58.
- 25 The printing wheels are supported against wobbling, despite their single short bearings, and despite the movable mounting of bearing 58, because the wheels rest directly on the base at their peripheries.
- 30 The squared lower end 56 of shaft 54 carries a spur gear 74 which meshes with the gear 48 previously referred to. These gears remain in mesh at all times. In Fig. 6, the gears are shown in separated position, and it will be seen that the teeth are long enough so that they are still in mesh. There is also enough tooth clearance to permit the desired closing movement of the printing wheels, and in Fig. 7 the printing wheels have been moved against one another, thus bringing the teeth into closer mesh. This, incidentally, brings the printing wheels into exact desired registration, for the teeth are so shaped that there is no appreciable sideward or rotative play when the wheels are moved into the close position shown in Fig. 7.
- 35 It is desirable to provide a detent action so that the printing wheels will naturally tend to stop on a letter rather than between letters when rotating the same by means of the knob 18. In the present case, two such detent wheels are used, but they function as one, for the wheels are mounted in superposition on the squared end 56 of the movable printing wheel. The detent wheels are placed on opposite sides of gear 74 and are made larger in diameter than the gear, thus providing a means for maintaining gears 48 and 74 in mesh even though they are quite thin, being formed of sheet metal, though of heavy gauge. Specifically, we provide an upper detent wheel 76 and a lower detent wheel 78, these wheels being exactly alike and being disposed above and below gear 74. The detent wheels overlap gear 48 and thus hold the gears 48 and 74 in edge-to-edge relation, as is clearly shown in Fig. 8 of the drawings.
- 40 A detent roller 80 cooperates with both detent wheels. It is carried on an arm 82 pivoted at 84 and normally urged toward the detent wheel by means of a spring 86.
- 45 Movable wheel 16 is moved by pusher 24 which in turn is slidable in a slot 25 in base 12 (Fig. 6). The pusher is arcuately shaped to mate with the periphery of wheel 16, as is best shown in Fig. 1. Moreover, the pusher is cut away, as is shown at 90 in Fig. 8, in order to clear the raised letters

on the periphery of the wheel. The pressure of the pusher is thus exerted on the periphery of the wheel near the top and bottom and without danger of mutilating the letters. The pusher is guided by the side walls of the slot in base 12. The part above base 12 is wider than the slot, thus preventing downward movement of the pusher, and a channel-shaped member 92 is secured to the bottom of the pusher, as is clearly shown in Figs. 6, 7, and 8, thus preventing upward movement of the pusher. The channel-shaped member 92 preferably functions as a support or housing carrying the detent mechanism previously referred to, and this has the advantage that the detent roller is pushed hard into the detent teeth at the time of the printing operation, thus insuring accurate registration. The resistance of the detent is reduced to a comparatively light amount when the printing wheels are separated, thus making it easy to rotate the wheels to the desired setting each time a new character is to be printed.

50 Operating handle 22 may be formed by pressing heavy gauge sheet metal in suitable dies. The handle is pivoted at 94 between ears 96 struck upwardly from base 12. The operating lever is connected to pusher 24 by means of a link 98 which may be formed of sheet metal bent to channel-shaped cross-section. The connection between the operating lever and the pusher will be evident from inspection of Figs. 2 and 8. It will also be evident that when the handle is depressed, thus moving it from the solid to the broken line position shown in Fig. 8, the pusher moves wheel 16 against wheel 14 with a very substantial increase in leverage. The motion of the handle may, if desired, be limited by an appropriate stop screw 100.

55 The tape is preferably made of a thin, soft metal. The roll of tape may be loaded into housing 30 by simply unscrewing the screw 102, best shown in Figs. 1, 3, and 4. When centering screw 102 is removed, the cover 104 of housing 30 may be lifted, whereupon a roll 106 of the metal tape may be dropped inside the peripheral wall 108 of the housing. This wall is interrupted to form 60 the discharge passage 110, best shown in Fig. 1. Cover 104 is flanged to fit around wall 108, but the flange is also interrupted at the discharge passage, as will be seen in Fig. 3.

65 The metal tape is led from housing 30 to feed rolls 26 and 28. These are preferably provided with a frictional surface and may, for example, be made of rubber. In the present case, only one of the feed rolls is positively driven, it being intermittently rotated by pawl and ratchet mechanism next described with particular reference to Figs. 6, 7, and 8 of the drawings. The lower end of the shaft of wheel 28 carries a ratchet wheel 112. This is surrounded by an oscillatable pawl guide 114. In the present case, the pawl consists of a pin 116 which also functions to pivot guide 114 to a link 118 which extends all the way back to the lower end 120 of the operating lever. Pawl guide 114 is slotted at 121 and the shaft 122 of the feed roller passes through the slot 121. A restoring spring 124 is tensioned between one wall of base 12 and the end of link 118. The main function of spring 124 is to pull the operating lever 22 to its upward position, as is shown in Fig. 8. However, referring to Fig. 6, it will be noted that spring 124 is not aligned with link 118, but instead is so directed as to tend to pull link 118 toward the left, as viewed in Fig. 6. In this way, spring 124 fulfills the auxiliary function of

moving pawl pin 116 against the teeth of ratchet wheel 112. Pawl pin 116 can move radially outwardly when passing backwardly over the pawl teeth, as is shown in Fig. 7, because of the slot 121.

On examining the drawings, it will be seen that downward movement of the operating handle 22 causes a rearward movement of link 118, and this causes the pawl pin 116 to be moved rearwardly over a ratchet tooth without, however, producing any movement of the ratchet wheel. During the upward or restoring movement of handle 22, the link 118 moves forwardly under the influence of spring 124, and at this time the pawl pin 116 moves ratchet wheel 112, thus feeding a new section of the metal tape to the embossing wheels preparatory to the next printing operation or the next depression of the operating handle.

Reverting now to Fig. 1, the tape may, if desired, be additionally guided by metal guide rollers 126. The shafts of these guide rollers also serve to hold a top bearing plate 128 in position, said bearing plate receiving the upper ends of the shafts of the feed wheels 26 and 28. Plate 128 also holds the metal tape against upward movement, the tape being guided between the top of base 12 and the bottom of plate 128.

After passing the printing wheels 14 and 16, the metal tape runs through the cutting-off mechanism 32. This mechanism comprises a pair of spaced die plates 130, said plates being cut out, as indicated at 132, to receive the punch or male die element 134. The punch 134 is secured to the sidewardly bent end 136 of a plate 138 which is slidable in a bearing or guide 140. Guide 140 is formed at the upper edge of a plate 142 secured to the side of base 12. An operating arm 144 is pivoted at 146 and is normally moved upwardly by a restoring spring 148. The upper end of arm 144 is bent sidewardly to form the handle 34 previously referred to. The slide bar 138 is connected to operating arm 144 by means of a pin 150, this pin preferably being received in a slot on arm 144 in order to allow for angularity of the arm during its operating movement. On examination of Fig. 2, it will be understood that upon depressing handle 34, the slide 138 is moved forwardly, thus forcing punch 134 through die plates 130. In accordance with regular die practice, the punch 134 has a configuration accurately fitting the die openings 132 in plate 130, and the metal tape has a corresponding portion thereof cut away, as is indicated in Fig. 5. The punch cuts away the part 152, thus providing the printed sections of tape with ornamental ends, as is indicated at 154.

It is believed that the construction and operation of our improved embossing machine, as well as the advantages thereof, will be apparent from the foregoing detailed description. The printing wheels are readily moved to set the same for the desired character to be printed, this being done by simply spinning the knob 18. Both wheels turn in unison because of their gear connection. The necessary gearing is simplified and reduced in cost by simply using two spur gears which may be stamped from heavy gauge sheet metal. The movable wheel is carried in a movable bearing but the high pressure printing movement of the wheels is not applied to the bearing. Instead, the operating handle moves a pusher which bears directly against the movable wheel at a point diametrically opposite the stationary wheel, thereby moving the wheels together for printing engagement. The wheels are

properly registered by the tightening of the gear mesh and by means of detent wheels which serve the additional function of keeping the spur gears in edge-to-edge mesh. The detent is yieldably moved against the detent wheels with a variable pressure, the pressure being very light when selecting the letters to be printed, but being suitably increased during the printing operation. This result is obtained by the comparatively simple expedient of mounting the detent on the 10 pusher block. The tape is fed with an intermittent step-by-step movement, it being moved during the upward or restoring movement of the operating handle. The printing wheels are supported against wobble and the tape is guided against transverse movement by utilizing the top of the base of the machine as a support for the printing wheels and the tape. The parts are all made of sheet metal shaped up in suitable dies, except for a few parts, specifically, the printing 20 wheels, the bearings for the same, and the pusher block, which, however, may also be made inexpensively by die-casting the same.

It will be apparent that while we have shown and described our invention in a preferred form, many changes and modifications may be made in the structure disclosed without departing from the spirit of the invention defined in the following claims.

We claim:

1. A toy embossing machine comprising stationary and movable printing wheels, and means to bring said wheels together for the desired printing operation, said means including a pusher block disposed near the periphery of the movable wheel at a point diametrically opposite the stationary wheel, an operating lever, and means whereby movement of the operating lever moves the pusher block against the movable wheel and further, and thereby moves the wheels into 40 printing engagement.

2. A toy embossing machine comprising stationary and movable printing wheels, means to rotate one of said wheels to print a desired letter, gearing for rotating said wheels in unison so as to keep the wheels in registration, and means to bring said wheels together for the desired printing operation, said means including a pusher block disposed near the periphery of the movable wheel at a point diametrically opposite the stationary wheel, an operating lever, and means whereby movement of the operating lever moves the pusher block against the movable wheel and further, and thereby moves the wheels into 50 printing engagement.

3. A toy embossing machine comprising relatively movable printing wheels rotatably mounted with their axes parallel, one of said wheels being journaled in a stationary bearing and the other in a movable bearing, said movable bearing being slidably mounted for bodily transverse movement of the movable wheel while maintaining the axes of the wheels parallel, means for rotating one of said wheels, directly meshing spur gears secured to said wheels, the teeth of said 60 gears being so large that they remain in mesh during movement of the movable wheel, an operating lever, and means whereby said operating lever moves the movable wheel toward the stationary wheel.

4. A toy embossing machine comprising relatively movable printing wheels, one of said wheels being journaled in a stationary bearing and the other in a movable bearing, means for rotating one of said wheels, sheet metal spur gears se- 75

- cured to said wheels in mesh, detent wheels formed of sheet metal and disposed on opposite sides of one of said spur gears, said detent wheels being larger in diameter than said one gear and overlapping the other gear, thereby keeping the gears in mesh, the teeth of said gears remaining in mesh during movement of the movable wheel, and a yieldable detent cooperating with the peripheries of the detent wheels.
5. A toy embossing machine comprising relatively movable printing wheels, one of said wheels being journalled in a stationary bearing and the other in a movable bearing, means for rotating one of said wheels, sheet metal spur gears secured to said wheels in mesh, detent wheels formed of sheet metal and disposed on opposite sides of one of said gears, said detent wheels being larger in diameter than said one gear and overlapping the other gear, thereby keeping the gears in mesh during movement of the movable wheel, a yieldable detent cooperating with the peripheries of the detent wheels, an operating lever, a pusher disposed near the periphery of the movable wheel 25 at a point opposite the stationary wheel, and means between said operating lever and pusher for moving the pusher and movable wheel toward the stationary wheel.
6. A toy embossing machine comprising relatively movable printing wheels, one of said wheels being journalled in a stationary bearing and the other in a movable bearing, means for rotating one of said wheels, sheet metal spur gears secured to said wheels in mesh, detent wheels formed of sheet metal and disposed on opposite sides of one of said gears, said detent wheels being larger in diameter than said one gear and overlapping the other gear, thereby keeping the gears in mesh, the teeth of said gears remaining in mesh during movement of the movable wheel, a yieldable detent cooperating with the peripheries of the detent wheels, an operating lever, a pusher block disposed near the periphery of the movable wheel at a point opposite the stationary wheel, and means between said operating lever and pusher block for moving the pusher block and movable wheel toward the stationary wheel, said detent being mounted on said pusher block.
7. A toy metal embossing machine comprising a generally flat horizontal base fixedly carrying one vertical bearing and movably carrying another vertical bearing, a printing wheel resting on top of said base and journalled in said fixed bearing, a mating printing wheel resting on top of said base and journalled in said movable bearing, a pusher slidably mounted on said base adjacent the periphery of the movable wheel at a point opposite the stationary wheel, means for rotating said wheels, a main operating handle, and appropriate linkage between said handle and said pusher.
8. A toy metal embossing machine comprising a generally flat horizontal base fixedly carrying one vertical bearing and movably carrying another vertical bearing, a printing wheel resting on top of said base and journalled in said fixed bearing, a mating printing wheel resting on top of said base and journalled in said movable bearing, a pusher slidably mounted on said base adjacent the periphery of the movable wheel at a point opposite the stationary wheel, means for rotating one of said wheels, gearing within said base for causing simultaneous rotation of the wheels, detent mechanism in said base for causing registration of the wheels, a main operating han-
- dle, and appropriate linkage between said handle and said pusher.
9. A toy embossing machine comprising a first printing wheel rotatable in a stationary bearing, a second printing wheel rotatable in a bearing mounted for movement toward or away from the first printing wheel, means for turning said wheels, a detent wheel mounted for rotation with said movable wheel, an operating lever, a pusher block disposed near the periphery of the movable wheel at a point diametrically opposite the stationary wheel, a detent yieldably mounted on said pusher block for cooperation with the detent wheel, and linkage whereby movement of the operating lever moves the pusher block against the movable wheel and further, and thereby moves the wheels into printing engagement.
10. A toy embossing machine comprising a first printing wheel rotatable in a stationary bearing, a spur gear rotatable with said printing wheel, a second printing wheel rotatable in a bearing mounted for movement toward or away from the first printing wheel, a mating spur gear rotatable with said second printing wheel and meshing with the gear of the first printing wheel, the teeth of said gears being so arranged that they remain in mesh when the wheels are separated and yet permit movement of the movable wheel toward the stationary wheel for the printing operation, means for rotating one of said wheels, an operating lever, a pusher block disposed at the periphery of the movable wheel at a point diametrically opposite the stationary wheel, and linkage whereby movement of the operating lever moves the pusher block against the movable wheel and further, and thereby moves the wheels into printing engagement.
11. A toy embossing machine comprising a first printing wheel rotatable in a stationary bearing, a spur gear rotatable with said printing wheel, a second printing wheel rotatable in a bearing mounted for movement toward or away from the first printing wheel, a mating spur gear rotatable with said second printing wheel and meshing with the gear of the first printing wheel, the teeth of said gears being so arranged that they remain in mesh when the wheels are separated and yet permit movement of the movable wheel toward the stationary wheel for the printing operation, means for rotating one of said wheels, a detent wheel mounted for rotation with said movable wheel, an operating lever, a pusher block disposed near the periphery of the movable wheel at a point diametrically opposite the stationary wheel, a detent yieldably mounted on said pusher block for cooperation with the detent wheel, and linkage whereby movement of the operating lever moves the pusher block against the movable wheel and further, and thereby moves the wheels into printing engagement.
12. A toy metal embossing machine comprising a generally flat horizontal base, a pair of printing wheels arranged with their axes perpendicular to the base and having large-diameter portions resting directly on top of said base, means for rotating said wheels to select a character to be printed, and means for relatively moving said wheels toward one another to print the character.
13. A toy metal embossing machine comprising a generally flat horizontal base having a downwardly turned peripheral flange, a pair of printing wheels arranged with their axes perpendicular to the base, said printing wheels each having a top face and a relatively broad downwardly extending periphery resting on said base as well

as a downwardly extending shaft at the center, 5 bearings for said shafts mounted on said base, one of said bearings being slidably mounted on the base so that the printing wheels may be relatively moved toward or away from one another, said bearings projecting upwardly from the base into the hollow space formed within the wheels, whereby the hollow interior of the base is left clear to receive the operating mechanism 10 of the embossing machine including appropriate gearing secured to the lower ends of the shafts of the wheels within the base.

14. A toy metal embossing machine comprising a generally flat horizontal base, a pair of printing 15 wheels arranged with their axes perpendicular to the base and having large-diameter portions resting directly on top of said base, means for rotating said wheels to select a character to be printed, means for relatively moving said wheels 20 toward one another to print the character, feed mechanism on said base near said wheels for feeding a metal tape between the wheels, said feed mechanism comprising a pair of feed wheels arranged with their axes perpendicular to the 25 base and having their lower ends resting directly on the base, whereby the lower edge of the metal tape rests on and is guided by the base as it moves through the feed wheels and through the printing wheels.

30 15. A toy metal embossing machine comprising a generally flat horizontal base fixedly carrying one vertical bearing and movably carrying another vertical bearing, a printing wheel having a large-diameter portion resting directly on top 35 of said base and journalled in said fixed bearing, a mating printing wheel having a large-diameter portion resting directly on top of said base and journalled in said movable bearing, means for moving the movable wheel toward or away from the stationary wheel, means for rotating said

wheels, a housing for a roll of metal tape disposed on top of said base, said roll of tape resting directly on said base, feed mechanism on said base near said wheels for feeding the tape from the roll to the wheels, the housing and 5 feed mechanism being so arranged directly on the base that the lower edge of the metal tape rests on and is guided by the base as it moves through the feed mechanism and the printing 10 wheels.

16. A toy embossing machine comprising relatively movable first and second printing wheels, means for turning said wheels in unison, a handle for moving said wheels together to print a character, a detent wheel mounted for rotation 15 with one of said wheels, a detent cooperating with said detent wheel, and linkage between said handle and detent for moving the same, the arrangement being such that the detent pressure is light when the wheels are being rotated 20 while separated, but is heavy during the printing operation.

17. A toy embossing machine comprising a first printing wheel rotatable in a stationary bearing, a second printing wheel rotatable in a bearing mounted for movement toward or away from the first printing wheel, means for turning said wheels in unison, a detent wheel mounted for rotation with one of said wheels, a pusher block 25 disposed near the periphery of the movable wheel at a point diametrically opposite the stationary wheel, means for moving the same to cause the wheels to print, a detent yieldably mounted on said pusher block for cooperation with the detent wheel, the arrangement being 30 such that the detent pressure is light when the wheels are being rotated, but is heavy when 35 printing.

WILLIS E. REXFORD.
RAYMOND LOHR.
